Primary Examiner — Robert M. Spear*(74) Attorney, Agent, or Firm* — Shaun K. Fox(57) **CLAIM**

The ornamental design for a tire, as shown and described.

DESCRIPTION

FIG. 1 is a side perspective view of a tire showing our new design;

FIG. 2 is a front elevational view thereof;

FIG. 3 is a side elevational view of the left side thereof;
FIG. 4 is a side elevational view of the right side thereof;
and,FIG. 5 is an enlarged fragmentary view thereof;
In the drawings, the broken lines depict environmental
subject matter only and form no part of the claimed design.**1 Claim, 5 Drawing Sheets**(56)
